A. Blipharm,
Attorney.

UNITED STATES PATENT OFFICE.

OSCAR V. HARGRAVE, OF MALDEN, MASSACHUSETTS.

MEANS OF DEFENSE.

1,381,301.

Specification of Letters Patent. Patented June 14, 1921.

Application filed August 23, 1920. Serial No. 405,505.

To all whom it may concern:

Be it known that I, OSCAR V. HARGRAVE, a citizen of the United States, and a resident of the city of Malden, in the county of Middlesex, and Commonwealth of Massachusetts, have invented certain new and useful Improvements in Means of Defense, of which the following is a full, clear, and exact specification.

10 When a person is traveling, either on foot or in a public conveyance, he is exceedingly helpless against the unexpected demand of a highwayman. He can make no move toward drawing a weapon in the eye of the 15 man who has him already covered by a gun.

The object of this invention is the construction of a means of self defense which can be carried, aimed and fired without attracting attention until the very moment of 20 the firing.

To this end, I provide a hand bag, grip, dress suit case or other article of luggage, with a fire-arm, preferably an automatic pistol, so disposed that while a person has 25 hold of its handle he can engage a finger with a small ring and by a slight pull thereon can discharge the pistol through a hole in the end of the grip, and if the latter has been casually swung around toward the 30 highwayman, the miscreant will be either shot or frightened away.

In the drawings forming part of this specification, Figure 1 is a side sectional view of a part of a dress suit case provided 35 with my means of self defense. Fig. 2 is a sectional elevation of the same looking at the muzzle-end of the pistol. Fig. 3 is a perspective view on a smaller scale showing the suit case being carried.

40 At one end of a suit case 1, preferably close beneath its top 2 is formed a box 3 provided with a hinged cover 4. Within this box is secured a fire arm 5, of well known form disposed to aim straight forward and to shoot through a hole 6.

For enabling the pistol to be fired at will, a ring 7 is located beneath the handle 9 of the suit case 1, in a position to be easily entered by the forefinger of the hand grasping 45 the handle, this ring being suitably connected with the trigger 10 of the pistol so that when pulled the pistol will be fired.

The manner in which this ring is connected with the trigger, as illustrated, consists 55 of a bell-crank lever 11 pivotally supported

at 12 and having its arm 13 provided with a lug or roll 14 immediately in front of the trigger 10, the long arm 11 of the lever being attached to a stem 15 depending from the ring 7.

Hence, when the ring 7 is pulled upward, the trigger 10 is drawn back and the pistol discharged.

I do not, however, restrict myself to the form of firearm selected for illustration, nor to the precise method of its discharge.

The hole 6 is normally covered by means of a flap 16 having a hole 17, and a section of elastic fabric 19 which permits the flap to be drawn upward for presenting its hole 70 17 in line with the hole 6; the flap being temporarily secured in this position by means of a projection 20 upon which the flap is impaled. When released from this projection, the elastic section 19 draws the hole 17 down below the hole 6 and thereby conceals the latter, an eye 21 through which the flap slides serving to retain the flap in place on the top of the case.

This means of protection is used as follows: If the owner is walking upon the street at a time when he may suddenly require protection, he carries the luggage 1 at his side in a customary manner, his hand 80 grasping the handle 9 and, if thought necessary, with his finger touching the ring 7.

He has previously pulled up and fastened the flap 16 to present the holes 6 and 17 in line, in order to be ready for contingencies.

If, now, a foot-pad or other dangerous 90 character suddenly appears and threatens his life, he simply introduces his finger in the ring 7, directs the suit case toward the miscreant's legs, and pulls upon the ring.

In case the owner of the suit case is traveling on a stage coach in a hold-up section of the country, he will hold the case in his lap directed toward the most probable source of danger, with the handle 9 conveniently located. Then if a hold-up occurs, he can 100 shift the suit-case to aim at the bandit and discharge the pistol.

What I claim is:

1. A suit case having a handle and a hole through one end of it, a box fixed within 105 said suit case adjacent said hole, a pistol fastened within said box aiming toward said hole, a bell crank lever pivotally supported within said box and having a projection engaging the trigger of said pistol, and an 110

22
operating member outside of the suit case beneath said handle connected with said lever for firing said pistol.

2. A hand bag having a hole at one point, 5 a fire-arm positioned in said hand bag to fire through said hole, means exterior to the hand bag for firing the fire-arm, and a flap having a hole through it, an elastic member attached to said flap and to the hand bag 10 acting normally to draw the flap to a place

where said holes shall be out of line but where the flap shall close the hole in the hand bag, and means for fastening the flap in a position which shall leave said holes in line.

15

In testimony that I claim the foregoing invention, I have hereunto set my hand this twelfth day of August, 1920.

OSCAR V. HARGRAVE.
